Primary Examiner — Keli L Hill(74) *Attorney, Agent, or Firm* — Raj Abhyanker, P.C.**CLAIM**

The ornamental design for a wireless speaker, as shown and described.

DESCRIPTION

FIG. 1 is a perspective view of a wireless speaker showing my new design;

FIG. 2 is a left view thereof;

FIG. 3 is a right view thereof;

FIG. 4 is a front view thereof;

FIG. 5 is a rear view thereof;

FIG. 6 is a top view thereof; and,

FIG. 7 is a bottom view thereof.

The broken lines shown in the drawings represent unclaimed portions of the wireless speaker and form no part of the claimed design.
